Primary Examiner — Michelle E. Wilson*Assistant Examiner* — Clese Moore, Jr.(74) *Attorney, Agent, or Firm* — Michael Best & Friedrich LLP(57) **CLAIM**

We claim the ornamental design for a slotted panel of a light fixture housing, as shown and described.

DESCRIPTION

FIG. 1 is a perspective view of a slotted panel of a light fixture housing embodying the present invention.

FIG. 2 is a right side view of the design shown in FIG. 1.

FIG. 3 is a left side view of the design shown in FIG. 1.

FIG. 4 is a rear view of the design shown in FIG. 1.

FIG. 5 is a top view of the design shown in FIG. 1; and, FIG. 6 is a bottom view of the design shown in FIG. 1.

The portions of the light fixture shown in broken lines form no part of the claimed design. The slotted panel is not visible in the view opposite FIG. 4.

1 Claim, 6 Drawing Sheets(56)
